UNITED STATES PATENT OFFICE.

BENJAMIN F. BLAKE, OF MARION, OHIO.

RAILWAY-CROSSING.

1,095,788.

Specification of Letters Patent.

Patented May 5, 1914.

Application filed February 4, 1914. Serial No. 816,591.

To all whom it may concern:

Be it known that I, BENJAMIN F. BLAKE, a citizen of the United States, residing at Marion, in the county of Marion and State 5 of Ohio, have invented new and useful Improvements in Railway-Crossings, of which the following is a specification.

The present invention relates to railway crossings, that is to the portion of railway 10 tracks where one of said tracks is arranged at an angle to the other track, and the object of the invention is to provide a bridge or crossing rail at the track which registers or aligns with the ends of the rails of one of 15 the main tracks to provide a continuation for the said track and which may be rotated to bring the same into register or alinement with the second rails or the main track, in accordance with the direction of travel of 20 the rolling stock over the said main rails, and whereby the shock and jar occasioned by the wheels of the rolling stock passing between the gaps and the ordinary crossing is entirely overcome and also whereby the 25 life of the bridge or cross rails is materially extended and danger of injury to the ends of the rails of the main track is effectively overcome.

With the above object in view, and others 30 which will appear as the nature of the invention is more fully disclosed, the improvement resides in the construction, combination and arrangement of parts set forth in the following specification and falling with- 35 in the scope of the appended claims.

In the drawings there has been illustrated a satisfactory reduction of the improvement to practice, but the nature of the invention is such that the details of construction there- 40 of may be varied, and so the drawings are to be understood as merely illustrative and that I am not to be restricted to the details of construction therein disclosed but am entitled to all such changes as fall within 45 the scope of my claims.

In the drawings: Figure 1 is a top plan view of a railway crossing provided with my improvement, the cap or shield being removed, Fig. 2 is a similar view showing 50 the short or turning rails out of register with the main rails and in the act of being swung into register with the said main rails. Fig. 3 is an enlarged sectional view taken on the line 3—3 of Fig. 1, Fig. 4 55 is a similar view also taken approximately on the line 3—3 of Fig. 1, but showing the

bridge rails elevated preparatory to the rotation of the same to bring the ends of the rails into register with the rails of the right angular main track, Fig. 5 is a central sectional view on the line 5—5 of Fig. 1, Fig. 6 is a horizontal sectional view on the line 6—6 of Fig. 5, Fig. 7 is a similar sectional view on the line 7—7 of Fig. 5, Fig. 8 is a detail enlarged view illustrating the toggle means for raising the structure to permit of the rotation of the bridge rails, Fig. 9 is a view illustrating hydraulic means for raising the said bridge rails, Fig. 10 is a section, similar to Fig. 6, but illustrating co-acting toothed wheels for imparting a rotary movement to the structure, Fig. 11 is a detail sectional view showing the means for securing the angular brace members to one of the bridge rails, and Fig. 12 is a perspective view of one of the socket members employed in the construction.

As is well known in track construction, where one railway crosses another, a space is provided at the crossing for the flanges 80 of the wheels of the rolling stock. It may also be stated that such crossings may be arranged at comparatively short intervals upon one of the tracks, and as the treads of the wheels of the rolling stock necessarily 85 sink between the spaces, the said treads become flattened or otherwise mutilated, while at the same time the rail ends being subjected to a continuous impact of force by the wheels soon break or become otherwise damaged. As a consequence, the cost of maintenance to such rail crossings reaches a considerable height, and furthermore, the flattening or mutilation of the car wheels not infrequently results in the breakage of the 90 same, and many railway wrecks have been traced to this cause. Furthermore, the shock and jar incident to the wheels passing over the gaps at the crossings shock the nerves of the passengers within the coaches, and 100 have become a source of annoyance to the traveling public.

With my improvement, now about to be described, the above objections are entirely overcome, and in addition thereto my device will serve as a protective means for preventing accidents due to side-on collisions at the crossing, as with a track constructed in accordance with my improvement the engineer of a train will know that it is impossible for him to make a crossing without having received the proper signal.

The main tracks or rails which cross each other are, in the drawings, indicated by the numerals 1 and 2 respectively, and the rails of the said tracks terminate adjacent each other, the said tracks being arranged at a right angle to each other, as illustrated in the drawings.

Arranged within the cap rails of either of the main tracks 1 and 2 are short rails 3, which, hereinafter, will be referred to as the bridge rails. These bridge rails 3 are of a length sufficient to fill the gap between the rails, and if necessary, to contact with the ends of said main rails, so that no space or very little space will be left between the bridge and main rails, the space in any instance, not being sufficient to permit of the treads of the rolling stock sinking below the surface of the heads of the rails, and as a consequence obviating the pounding or jar thus occasioned. The roadbed, at the gaps between the rails, has arranged therein, preferably in a concrete base, right angularly disposed I-beams 4 upon which the base flanges of the bridge rails rest, so that the said bridge rails will be amply supported and effectively sustained against downward movement or out of register with the main rails when the load of the rolling stock is delivered upon the said bridge rails.

The roadbed at the crossing is provided with a depression forming a chamber or manhole 5, and the cement bed 6 within which the I-beams 4 are planted may serve as the side walls of the said manhole 5, the lower wall of the same being preferably in the form of a thick iron plate 7 which rests upon a cement base 8. Embedded within the base 8 and extending through a central opening in the plate 7, is a vertically disposed shaft or axle 9, the same being constructed of metal and of a sufficient strength to withstand the strain to which it is subjected, and the said axle is round in cross section.

Mounted for rotation upon the axle 9, and arranged at the upper portion thereof is a hub 10, the same having secured thereon, and adjacent its upper face, a plurality of radiating brace bars 11, certain of which being connected directly to the inner faces of the bridge rails 3, preferably through the medium of removable brackets 12, while certain other of said brace members are secured, through the medium of brackets 13, to what I term socket members 14. These sockets 14, four in number, are disposed at a right angle to each other, and each at an equal distance from the axle 9 and the sleeve 10. The socket members have also connected thereto, preferably through the medium of brackets 15, short brace rods 16 which are connected preferably through the medium of brackets 17, to the inner faces of the bridge rails 3. In addition to the brace

members 11 and 16 I have found it desirable to provide additional brace members in the nature of truss rods 17, the same having one of their ends secured to the inner faces of the rails 3 and disposed therefrom at an angle thereto and extending within the manhole 5 and secured to the hub 10 through the medium of angle brackets 18, at a suitable distance below the brace members 11, the said arrangement being clearly shown in the drawings.

Planted within the cement bed 6 and arranged a suitable distance to the interior of the crossing are vertically disposed rods or shafts 19, the same having their upper ends cone-shaped, as at 20. The members 19 are four in number, and the same are disposed at right angles to each other and at an equal distance from each other and from the center of the shaft or axle 9, the arrangement being such as to receive the pockets 14 to retain the rails 3 in direct alinement and in register with the rails of either of the tracks 1 or 2, in accordance with the direction to which the bridge rails have been rotated. The manner of rotating the bridge rails and arranging the sockets upon the shafts 19 will presently be described. The socket members 14 preferably have their bores slightly cone-shaped so as to snugly receive the cone-shaped ends of the shafts or rods 19, and the lower ends of the said sockets 14 are preferably formed with continuous flanges 21 which are adapted to rest upon horizontally disposed plates 22 that are connected through the medium of brackets 23 to each of the rods or shafts 19, the flanges 21 resting upon the plates to provide additional means for sustaining the bridge rails firmly in position to withstand the load of the wheels of the rolling stock.

Secured to the hub 10 below the brace or truss rods 17 is a wheel 24. The said wheel may be grooved, as illustrated in the main figures of the drawings, for the reception of a cable 25, the said cable leading through a suitable opening in the manhole and roadbed, through a conduit (not shown) to a suitable source of power, such as a small engine or other motor (not shown). The operation of the motor, will, of course, rotate the hub 10 upon the axle 9, but as the device is held against revolution by the socket members 14 being engaged by the cone-shaped rods or shafts 19, means must be provided for elevating the structure to raise the socket members above the rods or shafts 19, and to accomplish this I provide an elongated extension or sleeve 26 which is arranged upon the axle 9 below the hub 10. The lower end of the hub 10 is preferably formed with an annular flange 27, while the upper end of the hub extension 26 is likewise provided with an annular flange 28, the flange 27 resting upon the flange 28, and if desired, a substan-

tially U-shaped band or ring 29 may engage with the peripheries of the flanges and the opposite faces thereof.

The hub extension 26, in the main figures of the drawings, is provided with a band 30 which has secured at diametrically opposite points thereon laterally arranged pins 31 which form the pivotal connection for a pair of links 32. These links are in turn pivotally secured to additional links 33, the links 33 being pivotally arranged in bearings 34 which are secured to the base plate 7, while the numeral 35 designates an operating rod or rods which are connected to the pivots of the links, and which, when pulled in one direction to strengthen the links will raise the hub extension 26 upon the axle 9, and likewise raise the hub 10 which, through the medium of the brace members 11 and 17, 20 raises the bridge rails 3 and the socket members 14 above the rods or shafts 19 to permit of the cable 25 being operated to rotate the bridge rails to bring their ends into register with the rails of the second main track, 25 and their sockets into position to be received upon the rods or shafts 19. When in such position, the rods 35 are operated to break the toggle lever connection between the links 32 and 33, permitting the device to lower by 30 its own weight to bring the bridge rails upon their supporting I-beams 4 and the hub extension 26 of the socket members upon the rest plates 22.

As shown in Fig. 9, the hub extension 26' 35 may have its lower end provided with a piston head or packing box and be arranged within a cylinder, the upper end of which being flanged as designated by the numeral 36, and the cylinder may be provided with 40 an inlet pipe 37 and an outlet pipe 38. When fluid is directed to the pipe 37, the hub extension will rise, elevating the device as just described, and when the fluid is allowed to flow through the outlet pipe 38, the device 45 will fall by gravity. Also, as illustrated in Fig. 10 of the drawings, the wheel 24' may have a toothed periphery, the said teeth being engaged by teeth upon a smaller wheel 39, the smaller wheel having an axle 40 which may be operated by any suitable 50 mechanism (not shown). The wheel 39, it is to be understood, is of a comparatively great thickness to permit of the vertical movement of the hub extension 10 and still retain 55 its teeth in engagement with the teeth of the wheel 24'.

In order to protect the structure from the elements as well as from the dust and dirt of the road, I provide the same with a cover 60 40', the top of which inclines in all directions downwardly from the center, so that the same will shed water, snow, etc., and the ends of the cover are further raised at an inclination and connected to the inner faces 65 of the rails 12, the said inclined ends being

indicated by the numeral 41. Also, to protect the manhole as well as the I-beam supports, I provide an angular shed 42 upon the outer faces of the bridge rails 3, the same terminating in vertically offset portions or 70 flanges 43 which rest upon and frictionally contact with plates 44 which are arranged upon the roadbed, the said plates having their inner edges flanged, as at 45, so that moisture cannot find ingress between the 75 edge of the member 43 and the manhole or the elements supported by the bed 6. The brace members 11 and the truss rods 17 serve as spokes which connect the bridge rails 3 with the hub.

From the above description, taken in connection with the accompanying drawings, the simplicity of the device as well as the advantages thereof will, it is thought, be perfectly apparent to those skilled in the art to 85 which such invention appertains without further detailed description.

Having thus described the invention, what I claim is:

1. In a railway crossing, main tracks arranged at an angle to each other, bridge rails between the rails of one of the main tracks and in registering alinement with the said rails, vertically disposed locking means for retaining the bridge rails in such alinement, means for elevating the bridge rails to bring the same out of engagement with the locking means, and means for rotating the bridge rails to bring the same in register but above the second main rails, means for 90 permitting the lowering of the bridge rails and to bring the same into engagement with the said vertical locking means for sustaining the said bridge rails in registering alinement with the said second main rails.

2. In a railway crossing, two main tracks arranged at an angle to each other, two bridge rails alining and registering with the tracks of one of the main rails, a hub, spokes upon the hub, said spokes connected with the bridge rails, and a shaft for the hub, and means for rotating the hub upon the shaft to bring the bridge rails into register with the rails of either of the main tracks.

3. In a railway crossing, two main tracks arranged at an angle to each other, two bridge rails between the rails of one of the main tracks and in registering alinement therewith, a shaft arranged central of the crossing, a hub upon the shaft, spokes for the hub, said spokes being connected with the bridge rails, socket members upon certain of the spokes, vertical rods upon the roadbed receiving the socket members to sustain the bridge rails in register with the main rails, means for raising the hub upon the shaft to bring the socket members out of engagement with the rod, means for revolving the hub to bring the bridge rails in alinement with the rails of the second main track,

and means for permitting the lowering of the hub upon the shaft to bring the socket members of certain of the rods for sustaining the bridge rails in register with the rails of the second mentioned track.

4. In a crossing, main rails having their tracks arranged at an angle to each other, said crossing having a manhole, an axle projecting through the manhole, a hub upon the axle, spokes radiating from the hub, short rails disposed between the rails of one of the main tracks and connected with the spokes, socket members having cone-shaped bores secured to certain of the spokes, cone-shaped rods arranged to receive the socket members, a wheel upon the hub, a sleeve upon the shaft and supporting the hub, means for raising the wheel upon the shaft to elevate the hub to bring the socket members out of engagement with the rods, means for actuating the wheel to rotate the shaft to bring the bridge rails parallel with the rails of the second named track, means for lowering the sleeve upon the shaft to allow the hub to gravitate to bring the cone-shaped sockets over the cone-shaped rods other than those previously engaged by the said cone-shaped members to retain the bridge rails in register with the rails of the second mentioned track.
5. In a railway crossing, two main tracks having their rails arranged at angles, bridge rails between the tracks of one of the main rails and arranged flush and in register with the said rails, I-beam supports for the bridge rails, the crossing having a manhole arranged centrally thereof, a shaft projecting vertically through the manhole, a hub upon the shaft, bracket members secured to the hub, horizontal brace members connected with certain of said brackets, and with the inner faces of the bridge rails, cone-shaped socket members secured upon certain of said braces, cone-shaped rods embedded within the crossing and engaging within the said socket members, plates upon the rods forming rests for the sockets, angular rods con-

nected with the bridge rails and with the remaining brackets upon the hub, means for raising the hub upon the axle to bring the socket members out of engagement with the cone-shaped rods, means for revolving the hub when in such position to bring the bridge rails above but in alinement with the rails of the second mentioned track, means for permitting the hub to drop by gravity upon the shaft to bring the sockets over certain of the cone-shaped rods to retain the bridge rails in register with the rails of the second mentioned track, a cover connected with the bridge rails and arranged over the manhole, a shed connected with the outer face of each of the bridge rails, plates upon the ends of the said rest, and said plates having their inner edges formed with vertical flanges.

6. In a railway crossing, two main tracks which have their rails arranged at an angle to each other and which terminate adjacent each other, bridge rails between the rails of one of the main tracks, an axle disposed centrally of the crossing, a hub upon the axle having its lower end provided with an annular flange, a sleeve upon the axle having its upper end provided with an annular flange upon which the flange of the hub rests, toggle levers, the upper links of which being pivotally connected with the sleeve, operating rods for the toggle levers, means for operating the rods to actuate the levers to raise the sleeve upon the shaft to elevate the hub, a wheel upon the hub, means for rotating the wheel, spokes upon the hub connected with the bridge rails, and vertically disposed means for sustaining the bridge rails in register with the rails of either of the main tracks.

In testimony whereof I affix my signature in presence of two witnesses.

BENJAMIN F. BLAKE.
